9 Claims. (Cl. 12—59.7)

This invention relates to apparatus for conditioning leather and, more particularly, to machines for tempering shoe uppers to distribute moisture through selected portions thereof.

A number of operations performed in normal shoe manufacturing processes require that certain portions of the shoe be conditioned to increase the workability of the leather. For example, the flexibility and stretchability of upper leather must be increased by conditioning to prepare it for the lasting operations. This is usually in addition to the normal mulling of the uppers prior to their assembly. The upper, or select portions, must be wetted to enhance that workability resulting from the initial mull. The need for such conditioning is even greater where no prior mulling has taken place. As noted above, one operation where such conditioning or tempering of shoe uppers is necessary is in the lasting of the shoe. The workability of the upper must be increased to facilitate the lasting operations which involve the stretching, flexing and compressing of the leather fibrils. Further, the grain area must be conditioned to avoid its cracking.

Heretofore, the normal procedure for conditioning an upper has been to place it in a container of water for extended intervals or in variously designed steam chambers. These methods were time consuming and relatively ineffectual. A recent revelation in the art of distributing moisture throughout leather has led the way to development of the novel apparatus disclosed hereinafter. The technical phenomenon which facilitates the implementation of the subject invention is that moisture applied to one surface of a permeable article of manufacture can be rapidly and uniformly distributed within the article by the establishment of an appropriate temperature gradient thereacross. The rapidity with which the moisture is dispersed is dependent upon the temperature differential constituting the gradient, the inherent character of the article, and the condition thereof prior to the operation. The moisture on the high temperature side of the article would have a higher vapor pressure than that on the low temperature side and, thus, a pressure gradient is produced as a result of the temperature gradient. This pressure differential or gradient drives the moisture into and through the article. Thus, the establishment of hot and cold reservoirs on opposite sides of a piece of leather or similar article of manufacture can be utilized to distribute water or other conditioning solutions applied to the surface subjected to the hot reservoir. The distribution of moisture is additionally effected by a "wicking action" or capillary action initially occurring at the exposed surface.

Accordingly, an object of the present invention is to provide a conditioning machine in which leather is tempered.

A further object of this invention is to provide a machine to accomplish the aforementioned object in a short interval of time.

A correlative object of the two above stated objects is to attain said objectives while accomplishing complete and improved tempering of the leather.

To this end and in accordance with a feature of the present invention, there is provided a machine for condi-

tioning leather comprising a first contact means having means for dispersing a conditioning solution to an article to be conditioned, means for heating said first contact means, and a second contact means having a lower operative temperature than said first contact means.

The above and other features of the invention including various novel details of construction and combinations of parts will now be more particularly described with reference to the accompanying drawings and pointed out in the claims. It will be understood that the particular machine embodying the invention is shown by way of illustration only and not as a limitation of the invention. The principles and features of this invention may be employed in varied and numerous embodiments without departing from the scope of the invention.

In the drawings:

FIG. 1 is a side elevation of an apparatus illustrating the subject invention, certain portions thereof being shown in section;

20 FIG. 2 is a front elevation of the apparatus illustrated in FIG. 1; and

FIG. 3 is a sectional view showing the shoe, upper pad portion of the machine of FIG. 1.

As illustrated in FIGS. 1 and 2, the operative instrumentalities of the machine, as hereinafter described, are housed in a chamber formed by sheet metal affixed to a framework 10. Accessibility to the operative instrumentalities is provided through an arcuate opening in the front of the machine, said opening not being shown in

30 FIGS. 1 and 2 as the sheet metal is removed to disclose the operative instrumentalities.

The instrumentalities utilized to effectuate the conditioning or tempering of a shoe upper essentially comprise moistening and heating contact means and cooperative contact means employed as a low temperature reservoir, said contact means being generally indicated by the reference characters 12 and 14, respectively in FIG. 2. The contact means 12 comprises a lower arcuate plate 16 secured to a bracket 18 which is integral with the framework 10. The plate 16 has secured thereto an arcuate plate 20 extending in spaced concentricity therewith over the upper arc thereof and along its length thereby defining an annular cavity 22. A plurality of arcuate heating elements 24 are mounted in the annular cavity 22 in spaced alignment along the length thereof. The heating elements are controlled by a thermostat 26 located on a control panel 28 of the machine. As best delineated in FIG. 2, the contact means 12 also comprises a curved resilient plate 30 located immediately above the plate 20 and generally concentric therewith. The plate 30 is mounted on the bracket 18 for yielding movement relative to the plate 20 by a plurality of wires 32 and 34 secured to the corners of the plate 30 and extending and affixed to outwardly projecting members 36 mounted on the bracket 18; only the forward-most wires 32, 34 being shown in FIG. 2. In the normal inoperative position of the machine, the plate 30 is displaced from the plate 20. A pad 38 of porous material is located on the upper surface of the plate 30.

The pad 38 functions to transmit conditioning solution to a shoe upper and preferably comprises a lower layer 40 (FIG. 3) of knitted glass, an intermediate layer 41 of polyurethane foam, and an upper layer 42 of cotton cloth. The conditioning solution is introduced to the pad 38 through an ellipsoidal pipe 43 interposed between the layers 42 and 41 having a plurality of perforations 44 in the upper surface thereof through which the solution passes, said pipe 43 extending from the rear of the pad 38. The pipe 43 is maintained in position by packing 39. In the operation of the machine, a conditioning solution such as water is supplied through the pipe 43 to

the upper layer 42 of the pad 38 and passes therethrough to be dispersed through an article to be conditioned.

The conditioning solution is supplied to the pipe 43 from a container 45 (FIG. 1) supported by the framework 10. A pipe 46 leads from a filter 47 in the container 45 to a reciprocating pump 48. A one-way valve 49 is provided in the pipe 46 to allow the conditioning solution to pass from the container 45 to the pump 48 but not in the reverse direction. Piping 50 joins the pump 48 to the pipe 43. A one-way valve 51 is provided in the piping 50 to permit flow from the pump 48 to the pipe 43. The pump 48 is operated by a drive cylinder 52 having a piston (not shown) operatively linked to said pump. The operation of the piston in the cylinder 52 is controlled by means hereinafter to be described in the description of the functioning of the contact means 14.

The contact means 14 is located above the contact means 12 for movement theretoward and therefrom, said movement effected by means to be hereinafter described. As illustrated in FIG. 2, the contact means 14 comprises an arcuate resilient plate 58 generally concentric with the plates 30, 20 and 16 and a layer 60 of resilient material such as rubber adhered to the lower surface of the plate 58. The contact means 14 is normally retained in an inoperative position displaced from the contact means 12, as shown in FIG. 2. The contact means 14 may, in the alternative, be provided with a cooling plate interposed between the plate 58 and layer 60, said plate being cooled by any convenient means.

In the operation of the operative instrumentalities described above, a portion of an upper S (FIG. 1) to be tempered is placed on top of the porous pad 38 with its flesh side in contact with the pad 38, tempering solution is supplied to the pad 38, the heating elements 24 are activated, and the contact means 14 is lowered into pressure exerting contact with the upper. The pressure exerted by the contact means 14 forces the resilient plate 30 into contact with the plate 20 thereby facilitating the transfer of heat from the heating elements 24 through the plate 30 to the pad 38. The pad 38 thus supplies the conditioning solution and acts as a high temperature reservoir while the layer 60 constitutes a low temperature reservoir thereby establishing a temperature gradient to distribute the conditioning solution through the exposed portion of the upper. The distribution of conditioning solution to the upper S is additionally effected by a "wicking action" resulting from contact of the upper S with the porous pad 38.

As stated above, the contact means 14 is movable toward and away from the contact means 12 between an upper inoperative position (FIG. 2) and a lower operative position (FIG. 1). A fluid operated system is employed to effectuate the movement of the contact means 14 and comprises a drive cylinder 70 having a piston (not shown) slidable therein, said cylinder 70 being mounted on a plate 72 secured to the framework 10 and supported by brackets 74 by securing means 76. A piston rod 78 is affixed at opposite ends thereof to the piston (not shown) within the cylinder 70 and a yoke 80. The yoke 80 comprises an essentially U-shaped member 82 secured at its central portion to the piston rod 78 and extending circumferentially about the arcuate plate 58. Studs 84, 84 (FIG. 2) are centrally affixed to the opposite terminal portions of the member 82 and extend perpendicularly thereto transversely of and in contact with the plate 58. Two leather straps 86, 86 are attached to the corresponding outer ends of the studs 84, 84 on opposite sides of the member 82 and pass over the arcuate plate 58. A rubber collar 88 surrounds the piston rod 78 and rests on top of the U-shaped member 82. The contact member 14 is moved into yielding contact with an upper S located on the pad 38 when the piston rod 78 is moved downwardly, the movement of the piston rod 78 being translated through the yoke 80 which is secured to the piston rod 78 by the studs 84, 84 mounted on the

yoke 80. The studs 84, 84 engage the plate 58 whereby the downward movement of the piston rod 78 is imparted to the member 14.

The contact member 14 is maintained in alined position relative to the contact member 12, removed from the operative position, and normally maintained in the upper position by the cooperative action of rods 90, 90, a cross-piece 92, and rods 94, 94. The rods 90, 90 are mounted for sliding movement in the plate 72 on opposite sides of the cylinder 70, the axis of said rods preferably lying in a plane coincident with that of the axis of the cylinder 70 whereby rotative movement of the member 14 relative to the member 12 is prevented. The cross-piece 92 is secured to the lower end portions of the rods 90, 90 below the plate 72 and has a centrally located aperture therein through which the piston rod 78 is freely slidable. The rods 94, 94, opposite ends of which are secured to the plate 72 and plate 58 establish a rigid linkage between the cross-piece 92 and the contact member 14, the rods 94, 94 being disposed on opposite sides of the piston rod 78 in a plane common to the axis of the piston rod 78 and normal to the plane in which the axis of the rods 90, 90, lie. When the piston rod 78 is moved upwardly from the operative position, the collar 88 engages the cross piece 92 whereby the upward movement of the piston rod 78 is translated to the member 14 through the rods 94, 94 thereby to remove the member 14 to the upper, inoperative position.

Pressure fluid is supplied to the upper end of the cylinder 70 through the piping 100. Any convenient means (not illustrated) may be employed to establish fluid pressure in the piping 100, and, consequently, the upper chamber of the cylinder 70. In the preferred embodiment of the subject invention, a first solenoid operated valve (not shown) is utilized to control the introduction of pressure fluid to the cylinder 70. A flow control valve 102 is positioned in the line 100. Piping 104 connects the lower chamber of the cylinder 70 to a second solenoid operated valve (not shown) and a pressure supplying source. A flow control valve 106 is positioned in the line 104. A pipe 108 leads from the upper chamber of the cylinder 52 to the second solenoid operated valve and a pipe 110 from the lower chamber thereof to the first solenoid operated valve. The introduction and exhaust of pressure fluid is thus coordinated in the cylinders 70 and 52. Thus, when pressure fluid is supplied to the lower chamber of the cylinder 70 to retract the contact means 14, pressure fluid is admitted to the upper chamber of the cylinder 52, the piston in the cylinder 52 is moved downwardly, and conditioning solution is drawn into the pump 48 from the container 45. Conversely, when pressure fluid is supplied to the upper chamber of the cylinder 70 to progress the contact means 14 into operative position, pressure fluid is admitted to the lower chamber of the cylinder 52, the piston in the cylinder 52 is moved upwardly, and conditioning solution is delivered from the pump 48 to the pipe 43. The solenoid operated valves are connected to an adjustable time switch (not shown) which is controlled by a push button 112. Power for operation of the above is controlled by the switch 114.

In the operation of the fluid pressure system delineated above, admission of pressure fluid to the upper portion of the cylinder 70 causes the piston rod 78 and, therefore, the yoke 80 to move toward the contact means 12. The yoke 80 progresses the contact means 14 downwardly into contact with a portion of an upper S located on the pad 38. When contact has been established between the contact means 14 and the upper S, continued application of pressure by the piston rod 78 causes the straps 86, 86 to press against the resilient plate 58 thereby to urge the layer 60 firmly against the upper S and said upper S against the porous material 42. The pressure exerted by the contact means 14 also results in the plate 30 contacting the plate 20, as described above. Thus, both the con-

tact means 14 and 12 are brought into complete surface engagement with the upper S.

Upon completion of the conditioning operation, pressure fluid is introduced to the lower chamber of the cylinder 70 and the yoke 80 is moved upwardly to permit the contact means 14 to be removed from contact with the upper S. The collar 88 then engages the cross-piece 92 thereby to retract the contact member 14.

A shoe to be conditioned is supported in position with its toe portion beneath the arcuate plate 16 by a platform plate 120 mounted on the bracket 18 and an adjustable support, generally indicated by the reference character 122. The support 122 maintains the heel of the shoe in position and comprises a horizontal rod 124 (FIG. 2) which extends across the front of the opening which provides access to the operative instrumentalities of the machine, said rod 124 being rotatively mounted in brackets 126, 126 secured to the framework 10, a sleeve 128 extending between the brackets 126, 126 concentric with the rod 124, and brackets 130, 130 freely mounted on opposite end portions of the rod 124 outwardly of the brackets 126, 126 in abutting relation therewith. The rod 124 is retained in position by a head portion 132 and an adjustable handle member 134 mounted on opposite end portions thereof. The handle member 134 is threaded on the rod for rotation whereby it can be employed to lock the brackets 130, 130 against the brackets 126, 126 in a desired angular position. The heel of a shoe to be conditioned rests upon a U-shaped tubular member 136 opposite sides of which are slidably accommodated in bores in the brackets 130, 130. The extended position of the member 136 can be determined by adjustment of the location thereof in the brackets 130, 130. The member 136 is secured in the desired position in the brackets 130, 130 by wing screws 138, 138. Thus, the angular position of the member 136 may be adjusted by loosening the handle member 134 and rotating the brackets 130, 130 and the extended position adjusted by loosening the wing screws 138, 138 and sliding the member 136 in the bores of the brackets 130, 130.

In the preferred embodiment of the present invention, a heater 142 (FIG. 1) is provided to heat the waist of an upper to activate thermoplastic adhesive previously applied thereto. The heater 142 is secured to the bracket 18 and extends horizontally therefrom under the support 122. The heater 142 comprises a frame 144 having a plurality of openings 146 in its upper surface and a heating element 148. The heating element 148 is controlled by an adjusting knob 150.

A cycle of operation of the above described machine is initiated after first activating the heating elements 24 and 138, the contact means 14 being in the upper inoperative position and the solenoid operated valves de-energized. A last L mounting a partially fabricated shoe is placed in position by the operator with the forepart of the upper S on the contact means 12. The solenoid operated valves (not shown) are then energized by depression of the button 112 thereby causing pressure fluid to be introduced to the upper chamber of the cylinder 70 and the lower chamber of the cylinder 52 through the first solenoid operated valve, opposite chambers of the cylinders 52 and 70 being vented to the atmosphere through the second solenoid operated valve. The contact means 14 is thus moved into operative position and conditioning solution is delivered to the pipe 43. After a pre-determined time interval registered on the timer (not shown), the solenoid operated valves are de-energized and pressure fluid admitted to the lower chamber of the cylinder 70 and upper chamber of the cylinder 52 through the second solenoid valve, opposite chambers of said cylinders 70 and 52 being vented to the atmosphere through the first solenoid operated valve. Thus, the contact means is returned to its inoperative position and conditioning solution drawn into the pump 48 in preparation for a subsequent usage.

Having thus described our invention, what we claim as new and desire to secure by Letters Patent of the United States is:

1. A machine for conditioning leather comprising a first contact means engageable with an article to be conditioned, said first contact means having means for dispersing a conditioning solution to a surface of an article to be conditioned, means for heating said first contact means, a second contact means engageable with an opposite surface of the article and having a lower operative temperature than said first contact means, and means facilitating the relative positioning of said contact means whereby a temperature gradient is established across an article to be conditioned during the conditioning portion of the operative cycle of the machine.
2. A machine for conditioning leather comprising a first contact means engageable with an article to be conditioned, said first contact means comprising means for dispersing a conditioning solution to one surface of an article to be conditioned and means mounting said dispersing means for transmitting heat thereto during the conditioning portion of the operative cycle of the machine, means for heating said mounting means, and a second contact means engageable with an opposite surface of the article and having a lower operative temperature than said first contact means.
3. A machine for conditioning leather comprising heating means and contact means having means for dispersing a conditioning solution to a surface of an article to be conditioned, heat transfer means mounting said heating means, and means mounting said dispersing means movable into contact with said heat transfer means whereby heat is transferred to said dispersing means during the conditioning portion of the operative cycle of the machine.
4. A machine for conditioning leather comprising heating means, a first contact means having means for contacting an article to be conditioned and dispersing conditioning solution thereto, heat transfer means mounting said heating means, and means mounting said dispersing means movable into contact with said heat transfer means whereby heat is transferred to said dispersing means during the conditioning portion of the operative cycle of the machine, means for supplying conditioning solution to said dispersing means, and a second contact means having a lower operative temperature than said first contact means, said second contact means being positioned to contact a surface of an article to be conditioned other than that contacted by said first contact means.
5. A machine for conditioning leather comprising a first contact means, said first contact means comprising means for dispersing a conditioning solution to a surface of an article to be conditioned and means mounting said dispersing means for transmitting heat thereto during the conditioning portion of the operative cycle of the machine, means for heating said mounting means, and a second contact means having a lower operative temperature than said first contact means, said second contact means being movable between an inoperative position displaced from said first contact means and an operative, article engaging position wherein said first and second contact means are in opposed contact with an article to be conditioned.
6. A machine for conditioning leather comprising heating means, a first contact means having means for contacting an article to be conditioned and dispersing conditioning solution thereto, heat transfer means mounting said heating means, and means mounting said dispersing means movable into contact with said heat transfer means whereby heat is transferred to said dispersing means during the conditioning portion of the operative cycle of the machine, means for supplying conditioning solution to said dispersing means, and a second contact means having a lower operative temperature than said first contact means, said second contact means being movable between an operative position displaced from said first contact means and an inoperative position.

contact means and an operative position in contact with a surface of an article to be conditioned other than that contacted by said first contact means.

7. A machine for conditioning leather comprising a first contact means, said first contact means comprising means for dispersing a conditioning solution to an article to be conditioned and means mounting said dispersing means for transmitting heat thereto during the conditioning portion of the operative cycle of the machine, means for heating said mounting means, and a second contact means having a lower operative temperature than said first contact means comprising a resilient contact member and means mounting said resilient contact member for movement between an inoperative position displaced from said first contact means and an operative position in pressure exerting contact with a surface of an article to be conditioned other than that contacted by said first contact means whereby said resilient member is urged into contact with the said surface.

8. A machine for conditioning leather comprising heating means, a first contact means having means for contacting an article to be conditioned and dispersing conditioning solution thereto, heat transfer means mounting said heating means, and means mounting said dispersing means movable into contact with said heat transfer means whereby heat is transferred to said dispersing means during the conditioning portion of the operative cycle of the machine, means for supplying conditioning solution to said dispersing means, and a second contact means having a lower operative temperature than said first contact means, said second contact means being movable between an inoperative position displaced from said contact means and an operative position in pressure exerting contact with a

surface of an article to be conditioned other than that contacted by said first contact means whereby said means mounting said dispersing means is urged into contact with said heat transfer means.

9. A machine for conditioning leather comprising heating means, a first contact means having means for contacting an article to be conditioned and dispersing conditioning solution thereto, heat transfer means mounting said heating means, and means mounting said dispersing means movable into contact with said heat transfer means whereby heat is transferred to said dispersing means during the conditioning portion of the operative cycle of the machine, means for supplying conditioning solution to said dispersing means, and a second contact means having a lower operative temperature than said first contact means comprising a resilient contact member and means mounting said resilient contact member for movement between an inoperative position displaced from said first contact means and an operative position in pressure exerting contact with a surface of an article to be conditioned other than that contacted by said first contact means whereby said resilient member is urged into contact with said surface and said movable mounting means moved into contact with said heat transfer means thereby to establish a temperature gradient across said article.
